UNITED STATES PATENT OFFICE.

ANDREW D. FULLER, OF WAKEFIELD, MASSACHUSETTS.

COIN HOLDER.

Application filed April 27, 1921. Serial No. 464,856.

To all whom it may concern:

Be it known that I, ANDREW D. FULLER, a citizen of the United States, and a resident of Wakefield, county of Middlesex, and 5 State of Massachusetts, have invented an Improvement in a Coin Holder, of which the following description, in connection with the accompanying drawings, is a specification, like characters on the drawings representing like parts.

My invention relates to holders for tokens, coins and similar articles, hereinafter generically referred to as coins.

My invention will be best understood 15 from the following description when read in light of the accompanying drawings of a specific embodiment of my invention selected for illustrative purposes, while the scope of my invention will be particularly 20 pointed out in the appended claims.

In the drawings:—

Fig. 1 shows a plan view of the submitted embodiment of my invention; and

Figs. 2 and 3 are respectively sections on 25 the lines 2—2 and 3—3 of Fig. 1.

Referring to the drawings:—

I have shown a member 1, which may be 30 of cardboard or other material stamped or otherwise formed to provide the radially extending members 3, so constructed as to form between them pockets for receiving and holding in spaced relation to each other the coins A. Each pocket so formed has the parallel side walls 5 and the semi-circular inner wall 7, these walls preferably 35 being spaced to form a pocket slightly larger than the coin. Constituting a bottom for the pocket I provide a disk 9 of cardboard or other suitable material and 40 for rendering visible the coins and retaining them in the pockets I provide a transparent cover in the form of a disk 11 of celluloid or other transparent material. The member 1, the bottom disk 9 and the 45 cover 11 I may glue or cement together or otherwise retain them in fixed relation to each other, so as to form a substantially integral structure.

Surrounding the edges of the coin carrier 50 above described is a rim relatively rotatable to the carrier and comprising rings 13, 15 and 17 of cardboard or other material glued or cemented together. The middle ring 15 is of a thickness substantially that of the 55 member 1 and substantially fits the periphery thereof, while the rings 13 and 17 re-

spectively are of substantially the same thickness of the disks 11 and 9 and fit the outer peripheries of the same. I have shown the member 1 of smaller exterior diameter 60 than the bottom and cover disks and it will be noted by this construction that the coin carrying member while rotatable relatively to the rim is securely held in position to be permanently surrounded by the latter. 65

Besides the casing afforded by the cardboard rim I may further provide a bottom casing member 18 secured to the rim by an encasing metallic rim 19, the latter having a portion 21 rolled over the edge of the member 18 and a portion 23 rolled over the edge of the transparent cover. The member 18 preferably constitutes a metallic mirror but may be of other material to provide a surface for advertising matter. The portion 23 of the rim, which may be of sufficient width to provide a surface on which may be printed or stamped advertising matter preferably terminates in such position as not to cover over the edges of the coins 80 and thereby to permit the entire portion of the latter to be exposed to view.

I further provide a washer 27 resting on the transparent cover and extending through the washer, the coin carrier and 85 bottom plate I provide a rivet or pin 29, the latter being freely rotatable relatively to the coin carrier. For preventing removal of the rivet for holding the parts in engagement I provide the former with the 90 heads 31 and 33.

The metallic rim 19 and the ring 15 of the cardboard rim are cut away to form a slot 95 35 to permit insertion of the coins into the coin pockets. It will be observed by my construction that by holding the assembled device in the hand, the coin carrier may be turned relatively to the casing by pushing the former around by means of the thumb resting upon the transparent cover. 100

In order that the device may serve to indicate money saved or spent, at the bottom surface of the pockets I print the days of the week or other periods of the calendar. When the coin is inserted it covers up the 105 surface so as to hide the characters printed thereon and when removed discloses the characters. If, for example, the device is filled with coins at the beginning of the week, at the end of the 110 week the device will indicate the days on which coins have been spent or not having

been spent, have been saved. On the surface of the member 1 adjacent the pockets I mark like characters for indicating to the user the pockets corresponding to the particular periods which periods the user would otherwise be unable to determine when all pockets have a coin inserted therein.

Although I have described one specific embodiment of my invention for purposes 10 of illustration it will be understood that I am not limited thereby to the specific mechanical details or materials and that wide deviations can be made therefrom without departing from the spirit of my invention.

15 Claims:

1. In a device of the character described, a revolute member having radially extended means for holding coins in spaced angular relation, a transparent cover carried 20 by said member for preventing displacement of said coins relatively to said member, and a casing having an open face adjacent said transparent cover and engaging the periphery of said revolute member.

2. In a device of the character described, a casing having an open face, a centrally located pivot carried by said casing, a coin carrying member carried by said pivot, and a transparent face carried by said member.

3. In a device of the character described, a casing having an open face, a centrally located pivot carried by said casing, and a coin carrying member having radially extending members for retaining coins in 30 spaced relation and carried by said pivot.

4. In a device of the character described, a member for holding coins in spaced relation, said member having surfaces marked to indicate periods of the calendar, and 40 means for retaining an inserted coin to cover said surfaces.

5. In a device of the character described, a member for holding coins in spaced relation and having a plurality of surfaces covered by said coins when placed thereon, and means for retaining said coins relatively to 45 said carrier and permitting their removal therefrom to expose said surfaces.

6. In a device of the character described, 50 a member for holding coins in spaced relation and providing surfaces adjacent the positions occupied by said coins and having characters indicating periods of the calendar marked on said surfaces.

55 7. In a device of the character described, a member for holding coins in spaced relation, said member having surfaces marked to indicate periods of the calendar and for retaining an inserted coin to cover said surfaces, said member also having surfaces on which are marked corresponding characters adjacent the inserted coin and at all times exposed to view.

8. In a device of the character described, 60 a member having coin receiving pockets on

its periphery, a casing surrounding the periphery of said member and having a radial coin slot, and means providing a pivotal mounting for said member on said casing.

9. In a device of the character described, 70 a member having coin receiving pockets, a casing for said member, and a pivot pin mounting said member for rotation in said casing.

10. In a device of the character described, 75 a coin carrying member of disk like form, a casing for the periphery of said member, a substantially annular groove in the periphery of said member, and said casing having a portion fitting said groove.

11. In a device of the character described, 80 a coin carrying member of disk like form, a casing for the periphery of said member, and said casing and member being so formed as to interlock with each other to prevent 85 axial displacement therebetween while permitting relative rotation.

12. In a device of the character described, 90 a relatively rotatable coin carrying member and casing, said coin carrying member comprising a disk formed with pockets cut radially inwardly on its periphery, members covering each side of said coin carrying member and secured thereto, said last named members being of greater outside diameter 95 than said coin carrying member, and a casing having a portion fitting between the projecting peripheral portions of said last named members.

13. In a device of the character described, 100 a relatively rotatable coin carrying member and casing, said coin carrying member comprising a disk formed with pockets cut radially inwardly on its periphery, members covering each side of said coin carrying member and secured thereto, a casing surrounding the periphery of said coin carrying member and having a radial coin slot, and means pivotally mounting said coin carrying member in said casing.

14. In a device of the character described, 110 a coin carrying member having angularly spaced coin receiving pockets with transparent covers, a casing for said coin carrying member, said casing being open on its side adjacent said transparent covers, a radial coin slot in the periphery of said casing, and a pivot rotatably mounting said coin carrying member in said casing.

15. In a device of the character described, 120 a rotary coin carrying member having coin pockets with transparent covers, a casing for said rotary coin carrying member, said casing surrounding the periphery of coin carrying member and being open on the side 125 thereof adjacent said transparent covers, a mirror for the back of said casing, and means clamping said mirror to the periphery of said casing.

16. In a device of the character described, 130

a rotary coin carrying member having coin pockets with transparent covers, a casing for said rotary coin carrying member, said casing surrounding the periphery of said coin carrying member and being open on the side thereof adjacent said transparent covers, a metallic mirror for the back of said casing, and a pivot pin extending through said mirror for rotatably supporting said coin carrying member.

17. In a device of the character described, a disk formed with pockets on its periphery, members cemented to opposite sides of said disk and covering said pockets, one of said members being of transparent material, a

casing for said disk and its covers, and said casing having a peripheral portion with a coin slot formed therethrough.

18. In a device of the character described, a disk formed with pockets on its periphery, 20 members cemented to opposite sides of said disk and covering said pockets, one of said members being of transparent material, a casing for said disk and its covers, and a pivot for rotatably mounting said disk and 25 its covers in said casing.

In testimony whereof, I have signed my name to this specification.

ANDREW D. FULLER.
